UNITED STATES PATENT OFFICE.

ALBEN E. LUNDELL, OF NEW YORK, N. Y., ASSIGNOR TO WESTERN ELECTRIC COMPANY,
INCORPORATED, OF NEW YORK, N. Y., A CORPORATION OF NEW YORK.

TELEPHONE-EXCHANGE SYSTEM.

1,263,083.

Specification of Letters Patent. Patented Apr. 16, 1918.

Application filed August 16, 1916. Serial No. 115,209.

To all whom it may concern:

Be it known that I, ALBEN E. LUNDELL, a citizen of the United States, residing at New York, in the county of Bronx and State of New York, have invented certain new and useful Improvements in Telephone-Exchange Systems, of which the following is a full, clear, concise, and exact description.

This invention relates to telephone exchange systems.

The object of this invention is to provide means whereby a line in trouble may be cared for.

A feature of this invention is a circuit arrangement by which calls to a line in trouble are diverted to a special operator, and by which a wire chief or an attendant is signaled, if through any means such trouble is removed.

A further feature of the invention is a circuit arrangement whereby a connecting operator's calling supervisory relay is not operated until the special operator plugs into the jack in which the line in trouble temporarily terminates, regardless of whether or not the terminals of such line are arranged for party line ringing.

The invention has been shown applied to a semi-automatic telephone exchange system, but is obviously capable of use with telephone systems of any type.

It is thought that the invention will be best understood from the following detailed description, reference being had to the accompanying drawings.

In the drawings, Figure 1 shows the substation apparatus of a calling and a called subscriber with portions of a connecting operator's cord circuit, and diagrammatically indicates portions of an automatic switch for establishing a connection to the called subscriber. Special connections at the distributing frame are indicated, such connections to be set up when the line of the called subscriber is in trouble. Fig. 2 shows a circuit arrangement for extending a line to an information operator and to a wire chief.

Let us now assume that the subscriber

whose substation apparatus is indicated at 1 desires to communicate with a subscriber 50 whose substation apparatus is indicated at 2, and that the line running to substation 2 is in trouble. The subscriber at 1 removes his receiver from the hook, whereupon a line signal 3 is displayed in the well-known manner. A connecting operator inserts a plug 4 into a jack 5 of the calling line, energizing answering supervisory relay 6 over the substation circuit from the battery of the usual repeating coil 7. The insertion of the plug 60 4 into the jack 5 energizes the cut-off relay 8 and the operation of the supervisory relay 6 prevents the lighting of the supervisory lamp 9 in the well-known manner. The operator then ascertains the number of the 65 wanted line and operates an automatic switch, the brush set of which is indicated at 10, 11 and 12. The automatic switch is controlled by circuits set up by a sequence switch (not shown), and after the brush set 70 is positioned on the terminals 13, 14 and 15 of the wanted line and such sequence switch arrives in position 16, ringing current is sent out over the line. The automatic selector switch and controlling sequence switch therefor are preferably of the type whose operation is described in Patent No. 1,168,319.

When the line running to substation 2 was reported out of order, special connections were set up to jacks 16 and 17 over 80 conductors 18, 19, 20 and 21 for a purpose to be described. Conductors 18 and 20 terminate in a plug 22, and conductors 19 and 21 terminate in a plug 23, which plugs are then permanently inserted in jacks 16 and 85 17. The above mentioned conductors are connected as indicated in the drawing, where the line enters the distributing frame, lines 19 and 21 being separated from one another by any suitable insulating device 24, lines 90 18 and 20 being similarly separated.

Going back to that stage of the operation in which the sequence switch arrives in its sixteenth position, a circuit is closed for ringing relay 25 from grounded battery, winding 95 95 of relay 25, armature and back contact of

relay 26, armature and back contact of trip relay 27, sequence switch contact 28, closed in the sixteenth position of the sequence switch, to ground. Relay 25 attracts its 5 armatures and ringing current is sent out over the following path: from ground, ringing generator 60, winding of relay 27, lower armature and front contact of relay 25, brush 11, terminal 14, conductor 18, tip of plug 22, 10 tip contact of jack 16, conductors 29 and 30, left-hand high resistance winding of relay 31, condenser 32, conductor 33, tip contact of jack 17, tip of plug 23, conductor 19, terminal 13, brush 10, upper armature and front 15 contact of relay 25, to ground. Sufficient current flows to operate a drop 34 controlled by relay 31, but since the left-hand winding of relay 31 is of high resistance, the trip relay 27 does not operate. The operation of 20 drop 34 closes a circuit from ground, drop 34 and its contact 35, windings of relays 36 and 37, to grounded battery. Relays 36 and 37 are energized, the operation of relay 37 causing the display of a line signal 38 in the 25 well-known manner. The operation of relay 36 will cause the trip relay 27 to energize over a circuit from ground, ringing generator 60, winding of relay 27, lower armature and front contact of relay 25, brush 11, terminal 14, conductor 18, tip of plug 22, tip contact of jack 16, conductors 29, 39, a 30 resistance 40, lower armature and front contact of relay 36, to grounded battery. Relay 27 attracts its armature, thereby removing the 35 shunt about relay 26, which then energizes in series with relay 25. When relay 26 attracts its armature, it shunts out the winding of relay 25, which deenergizes and cuts off the ringing current and connects the talking 40 strands of the conductors. At the same time the sequence switch is moved from position 16 to position 18, which is the talking position. This movement of the sequence switch is controlled by circuits not shown.

45 The connecting operator's calling supervisory signal 41 is not energized at this time, since its circuit is from grounded negative pole of battery, lower right winding of repeating coil 7, winding of relay 41, lower 50 armature and back contact of relay 25, brush 11, terminal 14, conductor 18, tip of plug 22, tip contact of jack 16, conductors 29, 39, resistance 40, lower armature and front contact of relay 36, to negative pole of grounded 55 battery.

It might be well to note at this time that if the station called is on a party line, the arrangement might be such that ringing current would come in over conductor 19, tip of 60 plug 23, tip of jack 17, conductor 33, resistance 42, upper armature and front contact of relay 36, to grounded battery as before. This circuit would allow trip relay 27 to operate, but would prevent the energization of supervisory relay 41 as before, since the 65 circuit of relay 41 would then again terminate on both sides in like pole of battery.

When the special operator at O is signaled by the operation of lamp 38, she inserts a plug 43 into jack 44 associated with lamp 70 38. A circuit is then closed for a relay 45 from ground, upper left-hand winding of repeating coil 46, tip of plug 43, tip contact of jack 44, conductors 47, 48, winding of relay 45, conductors 49, 50, ring contact of 75 jack 44, ring contact of plug 43, supervisory relay 51, lower left-hand winding of repeating coil 46, to grounded battery. At the same time a circuit is closed from grounded battery, right-hand winding of relay 31, 80 conductor 52, sleeve contact of jack 44, sleeve of plug 43, resistance 53, to ground. Relay 31 attracts drop 34 and restores this device and its associated signal 38 to its normal condition.

The energization of relay 45 closes an energizing circuit for calling supervisory relay 41 from grounded battery, lower right-hand winding of repeating coil 7, winding of relay 41, lower armature and back contact of relay 25, brush 11, terminal 14, conductor 18, tip of plug 22, tip contact of jack 16, conductors 29, 54, impedance coil 55, 90 armature and front contact of relay 45, conductors 56 and 33, tip contact of jack 17, 95 tip of plug 23, conductor 19, terminal 13, brush 10, upper armature and back contact of relay 25, upper right-hand winding of repeating coil 7, to ground. Supervisory relay 41 remains energized until the operator at O removes plug 43 from jack 44. The coil indicated at 55 is of comparatively low resistance but is of high impedance, so that it may remain bridged across the talking 100 circuit without interfering with the conversation.

The operator at O may now inform the calling subscriber that the desired line is out of order.

When plug 22 was inserted in jack 16, a 110 circuit was closed for lamps 57 and 58, the lamp 57 informing the operator at O that a line in trouble has been connected to jacks 16 and 17, and that she may expect calls over this line. The lamp 58 informs a wire chief, 115 a portion of whose cord circuit is shown at O', that a line in trouble has been connected to his position. A jack 59 is connected with the sleeve contacts of jacks 16 and 17 as shown in the drawing, Fig. 2. The wire 120 chief at O' then inserts a plug 61 into the jack 59, and is thereby able to test the line leading to substation 2 and ascertain the nature and extent of the trouble. While the plug 61 is in jack 59, a circuit is closed for 125 a relay 62 from grounded battery, winding of relay 62, sleeve contact of jack 59, sleeve of plug 61, resistance 63, to ground.

In order that the arrangement now to be described may operate successfully, it is to be assumed that the trouble on the line running to the subscriber at substation 2 consists of either a short circuit across the conductors, or else a heavy ground on the conductor to which conductor 20 is connected.

The wire chief at O' after having discovered the nature of the trouble, removes plug 61 from jack 59 and depresses locking keys 64 and 65. The removal of plug 61 from jack 59 results in the deenergization of relay 62, whereupon a circuit is completed for relay 66 from grounded battery, winding of relay 66, spring contact 67 of relay 62, conductors 68 and 69, sleeve contact of jack 16, sleeve of plug 22, conductor 20, to ground at the point of trouble, if such trouble is a ground. If the trouble is in the nature of a short circuit, the circuit just traced will be extended across such short-circuiting path to the other line conductor, conductor 21, sleeve of plug 23, sleeve contact of jack 17, conductor 70, and armature and back contact of relay 62, to ground. When the trouble is removed from the line, relay 66 will be deenergized, whereupon a circuit is closed for relay 71 and lamp 72 from grounded battery, winding of relay 71, lamp 72, armature and back contact of relay 66, key 65 in its depressed position, to ground. The lighting of lamp 72 informs the wire chief that the trouble has been removed and the energization of relay 71 completes a circuit from ground through a generator 73, condenser 74, bell 75, key 64 in its depressed position, and armature and front contact of relay 71, to ground. The bell 75 is thus caused to ring and may signal the wire chief at O' or call his attention to the lighting of the lamp 72.

The conductors 18, 19, 20 and 21 are usually connected at the point where the line in trouble enters the distributing frame. When the wire chief receives a signal indicating that the trouble has been removed, he causes the normal connections of the line to be reestablished at the distributing frame, and connections may be made thereto in the usual manner.

Instead of using a single switch as described in this embodiment of the invention, the connection might equally well be established over a train of automatic switches, the dotted lines at 76 and 77 indicating the possible presence of such switches.

What is claimed is:

1. In a telephone exchange system, calling and called lines, means for establishing special connections when a line is in trouble, an information operator's position, a wire chief's position, a signal at said wire chief's position, means for diverting a calling line to said information operator's position if the

called line is in trouble, and means for operating said signal should the trouble be removed. 65

2. In a telephone exchange system, calling and called lines, means for establishing special connections when a line is in trouble, 70 such connections terminating in plugs, jacks arranged to receive said plugs, a pair of conductors running from said jacks to an information operator's position, a second pair of conductors running from said jacks to a wire chief's position, a signal at said wire chief's position, means at said information operator's position to allow said information operator to inform the calling subscriber that the desired line is in trouble, and means 80 for operating said signal should the trouble be removed. 75

3. In a telephone exchange system, calling and called lines, means including a connecting operator's position for establishing 85 connections between said lines, a connecting cord circuit thereat including a calling supervisory relay and means for applying ringing current to the called line, means for establishing special connections when a line is in trouble, an information operator's position, a wire chief's position, a signal at said wire chief's position, means for diverting the calling line to said information operator's position if the line called is in trouble, 90 means for operating said signal when the trouble is removed, means for positively tripping said ringing current when applied to a line in trouble, and means for preventing the energization of said connecting operator's calling supervisory relay until said information operator plugs into the connection. 100

4. In a telephone exchange system, calling and called lines, means for establishing special connections when a line is in trouble, 105 such connections terminating in plugs, jacks arranged to receive said plugs, a pair of conductors running from said jacks to an information operator's position, a second pair of conductors running from said jacks to a wire chief's position, a signal at said wire chief's position, means at said information operator's position to allow said information operator to inform the calling subscriber that the desired line is in trouble, and means including a relay and a locking key for operating said signal, said relay being arranged to deenergize when the trouble is removed and establish a circuit through said key for operating the signaling device. 110

5. In a telephone exchange system, calling and called lines, means including a connecting operator's position for establishing connections between said lines, a connecting cord circuit thereat including a calling supervisory relay and means for applying ringing current to the called line, means for estab- 115
120
125

lishing special connections when the line is in trouble, an information operator's position, means for diverting a calling line to said operator's position if the line called is in trouble, means to connect said information operator to said calling line, means for positively tripping said ringing current when applied to a line in trouble, and means ef-

fective for both individual and party line ringing for preventing the operation of said supervisory relay until the information operator has established connection to the calling line.

In witness whereof, I hereunto subscribe my name this 15th day of August A. D. 1916. 15

ALBEN E. LUNDELL.
